CLAIM

The ornamental design for a car seat cover, as shown and described.

DESCRIPTION

FIG. 1 is a front perspective view of a car seat cover, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a plan view of the front in its unfolded state; and, FIG. 8 is a plan view of the rear in its unfolded state.

The short-dash broken lines in the drawings illustrate stitching and are part of the claimed design. The long-dash broken lines illustrate environment which form no part of the claimed design.

1 Claim, 8 Drawing Sheets
